(No Model.)

P. B. PERKINS.

HYDRANT.

No. 358,567.

Patented Mar. 1, 1887.

UNITED STATES PATENT OFFICE.

PAUL B. PERKINS, OF NORTH SPRINGFIELD, MISSOURI.

HYDRANT.

SPECIFICATION forming part of Letters Patent No. 358,567, dated March 1, 1887.

Application filed April 2, 1886. Serial No. 197,577. (No model.)

To all whom it may concern:

Be it known that I, PAUL B. PERKINS, of North Springfield, in the county of Greene and State of Missouri, have invented certain new and useful Improvements in Hydrants; and I do hereby declare the following to be a full, clear, and exact description of the invention, such as will enable others skilled in the art to which it appertains to make and use the same.

10 My invention relates to an improvement in hydrants, the object of the same being to provide a fire-hydrant that can be inspected or repaired and the main valve, cap, rod, and connecting parts removed without shutting off the water from the main.

15 A further object is to provide against loss of water in the event of accidental breakage of the stand-pipe of the hydrant and to remedy the defects heretofore experienced in similar 20 devices for the same purposes.

The accompanying drawing shows a vertical section of hydrant constructed upon my improved principle.

25 A is the base of hydrant, by which connection is made to the main. B is the stand-pipe, flanged at its lower end for attaching it to the base, and is sufficient in length below the level of the pavement to prevent freezing, and above for the convenience of connecting 30 the hose at the nozzle, one of which is shown at C.

35 D is a cap secured upon the top of the stand-pipe and protecting and covering the interior mechanism. This cap overlaps the edge or periphery of the stuffing-box F and locks the latter in place, and, together with said stuffing-box, supports the nut E, which latter is provided with reduced ends, which rest in bearings formed in the cap and stuffing-box.

40 G is the main valve, having rubber disk-face H. This valve is guided by wings I, formed on the inner face of the base, and is provided with an annular groove, J, which communicates with the drip-opening 2, formed in the base near the upper end thereof, so that when 45 the valve is seated the drip is opened and the water in the stand-pipe may drain out, thereby preventing freezing. When this valve is opened, the groove is elevated above the opening and the drip is immediately closed by the 50 portion of the valve G below the groove.

K is the secondary automatic valve, located

within the base below the valve G, and supplied with a similar rubber disk or bearing face. This valve is provided with a hollow spindle, L, fitting loosely into the socket L' in the base 55 A, and inclosing a spiral spring, which exerts an upward pressure and keeps the auxiliary valve constantly against the central point, G², of main valve G, so that it moves up and down on the opposite side of the common seat G' simultaneously with the main valve. The socket L' is in open communication at or near the bottom thereof with the chamber in the base, thereby avoiding liability of obstruction by sediment to the working of the valve. These 60 valves, as described, and the opening-nut E at top are all connected in the operation by means of stem M, having a screw-threaded upper end, which the nut E operates, the said stem being connected to the valve at the bottom by means of a key, 3. This stem is prevented from turning by means of a forked arm, N, fastened to the stem and straddling the projection 4 on stand-pipe.

65 O is a stop-bolt adjustably secured in the top of the nut E over the upper end of the stem M. This bolt is adjusted a sufficient distance into the nut E to stop the upward movement of the stem and main valve when the latter is open and in operation.

70 The operation is as follows: If the main valve lifts one inch for full opening, the distance from the top end of stem M to the bottom of the stop-bolt O should be one inch. Now, by turning the nut E the thread on same will 75 cause the spindle M to rise one inch, striking the end of stop-bolt, and the main valve will be wide open, allowing a free passage of the water. As the secondary valve is at least one and one-half inch below the seat when the main valve 80 is open, the secondary valve is still some distance away from its seat when the main valve is wide open. Now, if I desire to remove the main valve G, the cap, and stem from the hydrant, I unscrew and take out the stop-bolt O, 85 which permits the top of the stem M to rise sufficiently high to seat the secondary valve K against the under side of seat G', where it is held in place by the pressure of the water in the main from the stand-pipe. To replace 90 the parts, the main valve and stem are lowered into place until the central points of the main

valve sit in socket of the secondary valve K. The cap is then bolted in position and the nut E turned until the main valve is seated, when the stop-bolt O is replaced as before, and the 5 hydrant is ready for use.

I am aware that it is not broadly new to provide a hydrant with a secondary valve adapted to close and prevent the escape of water when the main valve is removed, and 10 hence I make no claim to such a construction, broadly.

Having fully described my invention, what I claim as new, and desire to secure by Letters Patent, is—

15 1. The combination, with a stand-pipe, a stuffing-box loosely mounted thereon, and a cap secured on the stand-pipe and locking the stuffing-box thereon, of the nut having reduced ends and journaled in the cap and stuffing-box, the 20 stop-bolt adjustably secured in the upper exposed end of the nut, the valve-stem, screw-threaded at its upper end and engaging the lower end of the nut, a valve secured to said stem and a second valve-stem, and a spring 25 for forcing the second valve upwardly.

2. The combination, with a base having a valve-seat, the latter having bearing-surfaces for valves on its opposite sides, and a stand-pipe, of the nut, a stop-bolt secured to the nut 30 for limiting the upward movement of the valve-stem, the valve-stem secured to the lower end of the nut and carrying a main valve adapted to rest against the upper face of the valve seat, the auxiliary valve adapted

35 to rest against the lower face of the valve-seat and engaging a projection depending from the main valve, whereby the auxiliary valve is moved downwardly by the main valve, and a spring for moving the auxiliary valve upwardly.

40 3. The combination, with the base having a socket, and a valve-seat located above said socket, the said valve-seat having bearing-surfaces for valves on its opposite sides, a stand-pipe secured to said base, a nut secured to the 45 upper end of the stand-pipe, and a stop-bolt adjustably secured in the upper end of the nut, of the valve-stem operated by the nut and carrying a valve adapted to rest on the upper face of the valve-seat, an auxiliary 50 valve adapted to be moved downwardly by the main-valve stem and having a hollow shank, the latter resting within the socket in the base, and a spring located within the hollow shank, substantially as set forth.

55 4. The combination, with the base having a series of wings and a drip-opening formed in one of said wings, of a valve having a peripheral groove, the latter adapted to register with the drip-opening in the wing when the 60 valve is in a closed position.

In testimony whereof I have signed this specification in the presence of two subscribing witnesses.

PAUL B. PERKINS.
